UNITED STATES PATENT OFFICE.

ANTON KULICH, OF BROOKLYN, NEW YORK.

BED-LOUNGE.

SPECIFICATION forming part of Letters Patent No. 508,548, dated November 14, 1893.

Application filed October 26, 1892. Serial No. 450,080. (No model.)

To all whom it may concern:

Be it known that I, ANTON KULICH, a subject of the German Emperor, and a resident of the city of Brooklyn, in the county of Kings and State of New York, have invented certain new and useful Improvements in Bed-Lounges, of which the following is a specification.

This invention relates to certain improvements in bed-lounges of that class, in which the lounge may be readily changed to a bed and vice versa from a bed into a lounge and in which the covered portions of the lounge are not in use and subjected to wear when the lounge is a bed, so that the cover remains for a longer time in good condition; and the invention consists of a bed-lounge composed of a main-frame which is provided with a detachable back which is made of an exterior frame and of a hinged and upholstered back-section. This back-section is adapted to be lowered into the main-frame after the seat-section which is hinged to the front-part on the main-frame is turned on its hinges in outward position. The seat-section is provided with pivoted legs by which the seat-section is supported when in position as a bed-section. The head-piece of the lounge is made of two sections, a stationary section, attached to the main-frame and a hinged section which is turned in outward direction and supported on a pivoted and spring-actuated plate that is attached to the outer corner of the seat-section, said hinged plate assuming a position at right angles to the seat-section. The hinged head-section is folded back, so that the seat-section can be readily returned into its normal position in the main-frame without being obstructed by said plate.

In the accompanying drawings, Figure 1 represents a perspective-view of my improved bed-lounge. Fig. 2 is a perspective-view, showing the lounge in the act of being changed into a bed. Fig. 3 is a vertical transverse-section on line 3 3, Fig. 1, showing the bed-lounge arranged as a lounge. Fig. 4 is a vertical longitudinal section, showing the lounge changed into a bed. Fig. 5 is a detail horizontal section on line 5 5, Fig. 3, showing the connection of the detachable back with the keepers at the rear-part of the main-

frame, and Fig. 6 is a side-elevation of the hinged and sprung-actuated corner-plate by which the hinged section of the head-piece is supported on the seat-section of the bed-lounge.

Similar letters of reference indicate corresponding parts.

Referring to the drawings, A represents the main-frame of my improved bed-lounge. To the rear part of the main-frame A are applied near the corners of the same two keepers a which are made in the form of angle-irons and which are firmly screwed to the rear-part of the main-frame A. The keepers a support the downwardly-extended ends of the legs b of a detachable frame B to the lower parts of which is hinged an upholstered back-section B'. The back-frame B with its hinged back-section B' can be detached from the main-frame A of the bed-lounge, so as to facilitate transportation. To the front-part of the main-frame A is hinged an upholstered seat-section C; which is turned in outward direction so as to form the outer bed-section. In its outwardly turned position it is supported on pivoted and folding legs C', of any approved construction, as shown in Figs. 2 and 4. After the seat-section C is moved into outward position, the hinged back-section B' of the frame B is moved in downward direction into the main-frame and supported by the same on a level with the outwardly-turned seat-section as shown in Fig. 4. The head-piece of the main-frame A is composed of a stationary section D, and of a hinged section D' which latter is hinged to the stationary section so that it can be swung in outward direction so as to rest on the outwardly-turned seat-section C when the lounge is changed into a bed. To the outer corner of the frame of the seat-section C is attached a plate D² to which a spring actuated plate D³ is hinged which is provided at its under side with a projection or stop that abuts against the stationary plate D² so as to support the hinged plate D³ at an inclination of the hinged head-section D' when pressure is applied to the plate D³. The hinged and sprung-actuated plate D³ is first pressed by hand into an inclined position until the hinged head-section D' is moved in outward position and rests on the inclined plate D³ which there-

by supports the head-section E' on the seat-section C, as shown in Fig. 2. When the seat-section C is to be returned into the main-frame, the head-section D' is first returned into position in the stationary head-section D, whereby the pressure on the hinged plate D³ is released and the latter moved by its spring into a position at right angles to the frame of the seat-section C, as shown in dotted lines in Fig. 6, so that the seat-section can be readily moved back into its position on the main frame A without any obstruction from the plate D³.

In the changing of the bed-lounge into a bed, the seat-section is first turned on its 15 hinges in outward position and supported on its pivot-legs, which are dropped into vertical position, as shown in Fig. 2. The hinged head-section D' is next turned over on its 20 hinges until it arrives at the inclined supporting-plate D³ of the seat-section. The hinged back-section is then lowered down into the main-frame, whereby its upholstered 25 rear-part assumes a position on a level with the upholstered portion of the seat-section. In this position a bed is formed in which all 30 the parts are upholstered and in which all the covered parts of the lounge are not exposed and subjected to wear while the lounge is used as a bed. When the bed has to be 35 changed back into a lounge, the hinged head-section D' is first turned back over the stationary head-section D. The back-section B' is then lifted up and replaced in position in the reclining back-frame and retained thereon by projecting ledges e at opposite ends of the back-section B', so as to prevent the back-section from being pressed into the back-frame B when leaning against the same during the use of the lounge. The seat-section 40 C is finally returned into the main-frame by placing the pivot-legs in the usual manner into position alongside of the bed-section and

then turning the seat-section over into the main-frame.

When the bed is changed into a lounge, 45 the covered parts which were at the under side, when the lounge was used as a bed, are exposed again to view. As the covered parts are not in use when the lounge is used as a bed, they are not subjected to wear and present 50 thereby always a neat and unsoiled appearance, the bed-lounge being of a comparatively simple and inexpensive construction, which can be readily changed into a bed or back into a lounge, as required. 55

Having thus described my invention, what I claim as new, and desire to secure by Letters Patent, is—

1. The combination, of a main-frame having a stationary head-section hinged to the front-end of the main-frame and provided with pivot-legs at its outer end, a head-section hinged to the stationary head-section of the main-frame, and a hinged and spring-actuated plate applied to the outer corner of the seat-section and adapted to support the hinged head-section when the same is moved in outward direction, substantially as set forth. 60

2. The combination of a main-frame being 70 a stationary head-section, a hinged seat-section, a hinged head-section and a hinged and spring-actuated rest-plate attached to the outer corner of the seat-section for supporting the hinged head-section, said rest-plate being 75 provided with a stop at its under side, substantially as set forth.

In testimony that I claim the foregoing as my invention I have signed my name in presence of two subscribing witnesses.

ANTON KULICH.
